UNITED STATES PATENT OFFICE.

HANS MÜLLER, OF MUNICH, GERMANY.

BOX FOR STORING FURS.

Application filed July 8, 1926, Serial No. 121,151, and in Germany March 17, 1926.

This invention relates to a box for storing furs so that they are securely protected against moths. This box saves the expenses for preserving furs in store rooms and it is 5 easy to manipulate, of light weight, cheap to manufacture, occupies little space and of great durability.

The box for storing furs consists of a frame of wooden laths covered with plates 10 of wood ends. The lid consists also of a frame filled with a plate of wood ends said frame being guided by a tongue and groove 15 guiding in the laths of the frames of the short sides of the box and engaging with a groove in the top lath of one long side. The lid is locked in the closing position by means 20 of a chub-lock and of a tongue which is arranged on a bar fixed to a lath of the rear long side and designed to engage with a groove of the lath of the long side of the box frame. The joints of the lid are thus secured against penetration of dust and 25 moths. On the inner surface of one short side of the box hooks or the like are fixed on which the furs can be suspended, and for holding fur-jackets an arm is hingedly fixed 30 on the one long side of the box at half the height of the same, said arm being supported by an abutment on the opposite wall.

An embodiment of the invention is shown, by way of example, in the accompanying drawing in which—

Fig. 1 shows in front elevation the closed fur box.

Fig. 2 is a side elevation.

Fig. 3 is a section on line III—III of Fig. 1.

Fig. 4 is a front elevation of the fur box the lid having been removed.

Fig. 5 illustrates how the lid is guided in the upper and lower short side of the box.

The fur box consists of a frame made from wooden laths *a* covered with plates *b* of wood ends. The plates might be varnished. They are of greater durability than the commonly used walls of cardboard, hard wood, leather, fibre or the like and possess greater resistance against cracking.

The lid consists of a frame covered with

a plate *c* of wood ends. The laths *d* of the frame at the short sides of the lid are guided by tongue and groove in the frame laths *e* and the long lath *f* of the slideable lid and that of the frame *g* have also tongue and groove. On the long lath *h* of the slideable lid a bar *m* is fixed which has a tongue *k* engaging with a groove *l* of the lath *i* of the box-frame. A chub-lock *n* with hinged eye *o* serves to lock the lid in the closed position. A handle *p* is sunk into the long lath *h* of the lid.

On the inner surface of the short side *q* hooks *v* are fixed to which furs are to be suspended. At half the height of the long sides of the box a rod *s* is hingedly fixed 65 which rests upon an abutment on the opposite long side and is designed to hold short fur jackets or the like. Front ledges *u* are fixed on the outer surface of one short side and on the rear long side to protect the box 70 against damage.

The box, if it is in horizontal position, rests upon the front ledges in the back wall, and in this case the furs can be placed into the box as into a trunk.

Alder wood is preferably used for the plates.

I claim:—

A fur box comprising in combination a frame of wooden laths forming the back, the two long sides and the two short sides, the top lath of the two short sides and of the one long side having each a groove in the inner surface, plates of alder wood ends filling said frame, a lid consisting of a frame of wood laths covered with a plate of alder wood, a tongue on the lath of each short side of the frame and on the lath of the inner long side said tongues being designed to engage with said grooves in the top laths of the box frame, a chub-lock for locking said lid in the closed position, a bar fixed in the long side of said lid frame and engaging with the groove of the lath of the corresponding long side of the box frame. 95

In testimony whereof I affix my signature.

HANS MÜLLER.
